UNITED STATES PATENT OFFICE.

HARRY A. STONE, OF NEW YORK, N. Y., ASSIGNOR TO COLLAPSO PRODUCTS COMPANY, INC., OF NEW YORK, N. Y., A CORPORATION OF NEW YORK.

COMBINED TABLE AND EXTENSION-LEAF.

1,234,103.

Specification of Letters Patent. Patented July 17, 1917.

Original application filed March 10, 1913, Serial No. 753,374. Divided and this application filed October 31, 1913, Serial No. 793,464. Renewed December 18, 1916. Serial No. 136,816.

To all whom it may concern:

Be it known that I, HARRY A. STONE, a citizen of the United States, residing at New York, county of New York, and State 5 of New York, have invented certain new and useful Improvements in Combined Tables and Extension-Leaves, of which the following is a specification.

This invention relates to combined tables 10 and extension leaves.

My object is to provide a combined table and extension leaf; more particularly, a foldable skeleton table top composed of foldable arms, combined with a foldable extension leaf of improved construction, whereby the leaf may be folded into compact relation to the table top and folded with the latter, or, extended for use when the table top is in extended condition.

20 The invention consists of the combination with the table top, of a foldable extension leaf adapted to carry out the foregoing object and, more particularly, it comprises the leaf construction and skeleton table top 25 construction therewith combined in the manner substantially as hereinafter set forth. I do not, however, limit myself, except where so specified in the claims, to the precise embodiments of table top and leaf hereinafter described.

The present invention is a division of my co-pending application, Serial No. 753,374, filed March 10, 1913, and of my Patent No. 106,547, dated June 24, 1913.

35 In the accompanying drawings:

Figure 1 is a side view partly in section, showing a table having a foldable table top with which the foldable extension leaf is combined;

40 Fig. 2, a plan view thereof, the leaf being in extended condition;

Fig. 3, a detail view of the extension leaf folded against the parts of the skeleton table top; and

45 Fig. 4, a detail of a connection between the brace and an arm.

The folding table has folding legs 1 pivoted to ears 3 on a head 2. Fitting down over head 2 is a slid able shell 4 having radial grooves 6. Pivoted at 7 to suitable ears on the head 2 or shell 4 are arms 8 whose inner ends lie in the grooves 6, thus bracing the arms 8 and relieving the pivots 7 of strain. As shown in Fig. 4, the arms 8 are

hollow and have a slot 9 in their lower face. 55 Each brace 10 has a reduced end 11 (Fig. 4) projecting through slot 9 and provided with a pin 12. Suitable supporting means, such as 14, are provided on the legs 1 as a rest for the braces 10.

60 The above is a description of one of several forms of folding skeleton top tables of which a certain one is set forth in my application Serial No. 753,374, filed March 10, 1913; others appearing in my Patent No. 106,547, dated June 24, 1913, with which the extension leaf may be combined, but the extension leaf may be combined with other tables and I do not limit the combination of the leaf to the tables enumerated.

70 The extension leaf may be applied to the ends of any two of the arms 8.

The extension leaf is composed of members 37 pivoted to the ends of the arms 8 at 38, the members 37 having no connection 75 with each other. Each member 37 carries articulated members 39 which can be opened out to form a skeleton or may be folded against the member 37 to which they are attached and in substantial extension or alinement with the arms 8 so as to form continuations thereof adapted to be folded with said arms and with the braces 10. Fig. 2 shows the extension leaf in extended arrangement ready for holding papers or 80 articles and Fig. 3 discloses its arrangement when folded. When folded, the articulated members 39 fold against the member 37 which carries them.

I may provide in two of the arms 8, the 90 depressions 40 adapted to receive the rear legs of the typewriter. At the ends of the remaining arms 8, are overhanging flanges 41 adapted to engage the front legs of the typewriter. The flanges 41 are particularly 95 designed to engage and hold against tipping the legs of those typewriters which have off-set parts or feet. The table may be used without the flanges 41 and depressions similar to the depressions 40 may be substituted 100 to adapt the table for the support of any standard typewriter, or, other means may be employed for attaching the typewriter to the arms 8.

Having thus described my invention, what 105 I claim as new and desire to secure by Letters Patent, is:—

1. The combination with foldable legs, of

a table top having independently foldable arms, foldable braces for supporting the arms from the legs, and a foldable extension leaf consisting of two groups of relatively foldable jointed sections, the groups being respectively connected to and carried by adjacent ones of said foldable arms and the sections of the respective groups adapted to fold alongside the said arms and to be folded independently with them or to be extended so that the sections of the respective groups collectively constitute a leaf.

2. In combination with foldable legs, of a folding table whose top comprises foldable arms adapted for general lateral arrangement for use as a top or for folding into general upright disposition, foldable braces for supporting the arms from the legs, and

an extension leaf composed of two groups of relatively foldable jointed sections, the respective groups being, as a unit, jointed to, carried by, and foldable into upright disposition with certain of said foldable arms and adapted to fold alongside the arms or to be extended laterally so that the sections of the respective groups collectively constitute an extension leaf for the table top when the arms of the latter are in laterally extended disposition.

In testimony whereof, I hereunto affix my signature in presence of two witnesses.

HARRY A. STONE.
